UNITED STATES PATENT OFFICE.

FREDERICK GROVER, OF LEEDS, ENGLAND, ASSIGNOR TO THE FORGROVE MACHINERY COMPANY, LIMITED, OF LEEDS, ENGLAND.

LABELING AND WRAPPING MACHINE.

No. 822,118.

Specification of Letters Patent.

Patented May 29, 1906.

Application filed September 30, 1905. Serial No. 280,785.

To all whom it may concern:

Be it known that I, FREDERICK GROVER, a subject of the King of Great Britain, residing at Leeds, in the county of York, England, have invented a certain new or Improved Labeling and Wrapping Machine, of which the following is a specification.

This invention relates to a new or improved machine, as hereinafter described, primarily intended for wrapping and affixing labels around rectangular tablets, said machine being also applicable for wrapping rectangular bodies, such as chocolate tablets, in a covering material, such as tin-foil.

The machine consists, essentially, of a tray adapted to deliver a length or strip of labels to a pair of feed-rollers which deliver the strip in an upstanding position into a pocket, a horizontal knife working through a slot or gap in the said pocket for severing or subdividing the labels, a traveling belt for feeding the tablets up against a fixed stop, a pusher for carrying the first tablet and the subdivided label through an opening formed in the pocket so as to wrap the upper portion of the label around the forward end of the tablet and leave the lower portion of the label, which is then gummed, depending within the pocket itself, a gripper adapted to receive the partially-labeled tablet and carry it downward with the rear edge of the tablet and its label against a stationary curved plate to partially bring the rear portion of the label around the rear end of the tablet, and means for completely turning down the rear portion of the label over the tablet and causing the two portions of the label to adhere together.

Figure 1 is a side elevation. Fig. 2 is a plan. Fig. 3 is a sectional side elevation taken on the line A B of Fig. 2. Fig. 4 is a sectional plan taken on the line C D of Fig. 3, and Fig. 5 is a front elevation of a tablet-labeling machine constructed in accordance with my invention. Figs. 6, 7, 8, and 9 are perspective views, illustrating the different stages in the process of wrapping and affixing the label around the tablet.

In the drawings I have shown a machine for treating two tablets simultaneously, which machine consists of two side frames 1, held together at a suitable distance apart by means of stay-rods 2, the frames 1 being

formed having their upper members 1^x situated at an angle or sloping from the back downward and terminating in a curve with their front vertical members. Between the upper sloping members 1^x of the frames 1 are provided inclined cross-stays 3, on which is mounted a tray 4 for the reception of the lengths or strips of labels. The tray 4, which is provided with a hinged clip 4^x and guides 4^y for the strips, is situated between guides 5, located on the stays 3 so as to be capable of a sliding movement on the latter, which sliding movement is given to the sloping tray 4 at the required times by an engaging arm 6, pivoted on a transverse rod 7, through the medium of a runner 8 on the said arm 6, and a time-cam 9 located on a transverse shaft 10, which shaft 10 is driven by spur-gearing 11, transverse shaft 12, bevel-gearing 13, vertical shaft 14, bevel-gearing 15, longitudinal shaft 16, and bevel-gearing 17, from a main shaft 18, provided with a driving-pulley 19.

In front of the tray 4 and secured to the frames 1 is a curved guide-plate 20, and at the base of the guide-plate 20 are situated feed-rollers 21 22, the roller 21 being intermittently driven at a suitable speed by spur-gearing 23 from the transverse shaft 12, while the rollers 22 are set up to the roller 21 by a spring-plunger arrangement 24, so as to be driven by friction. Below the feed-rollers 21 22 are two vertically-arranged receptacles or pockets 25, across which is formed a transverse slot or gap 26, through which a horizontal knife 27, pivoted at 28, is free to work intermittently at the required times through the medium of a link 29 and a lever 30, pivoted on a stud 30^x, so as to be operated in one direction by a spring 31 and in the opposite direction by a cam 32, located on the transverse shaft 12, while at a suitable distance below the knife 27 the pockets 25 are divided by transverse openings 33, and immediately in front of these openings 33 and transversely across the front of the machine is an endless traveling belt 34, adapted to feed the tablets up to a stop 35, which belt 34 is supported by a stationary tray 36 and carried by a pulley 37, which is driven from the vertical shaft 14 by bevel-gearing 38, longitudinal shaft 39, pulley 40, cord 41, and pulley 42.

Between the side frames 1 and at the back of the pocket-openings 33 is arranged a double gripper 43, which is carried by a series of pivoted levers 44, 45, 46, and 47, forming a parallelogram, the upper end of the lever 45, which is pivoted on the transverse rod 7, being provided with a runner 48, engaging a cam 49, situated on the main shaft 18, and being provided with a spring 50 for keeping the runner 48 in contact with the said cam 49, while the lever 47, which is pivoted on a transverse rod 51, is provided with a runner 52, engaging a cam 53, situated on a transverse auxiliary shaft 54, which latter is driven from the longitudinal shaft 39 by bevel-gearing 55. On the auxiliary shaft 54 is mounted another cam 56, engaging a runner 57 of a rocking arm 58, pivoted on a stud 59, the free end of which arm 58 is connected, by means of a rod 60, to an arm 61 of a double lever 62, pivoted on a transverse rod 63, which levers 62 carry a double pusher 64, which is located immediately in front of the traveling belt 34 in a position directly opposite the openings 33 formed in the pockets 25, and the arm 61 is provided with a spring 65 for keeping the runner 57 of the arm 58 in contact with the cam 56, while on the rod 63 are pivoted two arms 66, carrying a pair of rollers 67, adapted to run on a gumming-pad 68, located immediately in front of the lower or open parts 25^x of the pockets 25. On the inner side of the pockets 25, below the openings 33, is located an inwardly-curved plate 69, and near the bottom edge of the plate 69 a trough-like channel or conductor-spout 70 is provided, having a pair of inner guide-rails 71, over which a pair of stationary brushes 72 are mounted, while in between the guide-rails 71 are a pair of endless chains 73, mounted on wheels 74 75, carried on transverse shafts 76 77, which chains 73, formed with teeth 78 at intervals in their length, are driven from the auxiliary shaft 54 by a chain 79. The chain-shaft 77 is provided with a cam 80, engaging a runner 81 on one of the arms 66, carrying the gumming-rollers 67.

In action the machine works as follows: Two lengths or strips of labels 82 having been placed in the tray 4 beneath the hinged clip 4^x, as shown in broken lines at Fig. 2, the said tray 4 is slid downward on the inclined cross-stays 3 by reason of the rotating cam 9 allowing the tray-engaging arm 6 to rock forward, whereby the strips 82 are thus caused to slide downward over the guide-plate 20 and engage between the rotating feed-rollers 21 22, which then deliver the said strips 82 in an upstanding position into the vertical pockets 25, when the horizontal knife 27 is operated, through the medium of the rotating cam 32, lever 30, and link 29, so as to pass through the transverse slot or gap 26 and sever the strips 82. The subdivided labels 82 are now

held in a vertical position by the pockets 25 themselves, and simultaneously with these movements the tablets 83 are fed forward by the traveling belt 34, so that the first tablet 83 rests against the stop 35, with the first and third tablets directly opposite the transverse openings 33, formed in the pockets 25, as shown in broken lines at Fig. 4. The pusher 64 now moves inward by reason of the rotating cam 56 operating the rocking arm 58, rod 60, arm 61, and levers 62, so as to move the tablets 83 forward against the upstanding labels 82 (see Fig. 6) and then carry the tablets 83 and their labels 82 through the transverse openings 33 in the pockets 25, so that the upper portions of the labels 82 are wrapped around the forward ends of the tablets 83 and leave a portion of the lower ends of the said labels 82 depending within the pockets 25. (See Fig. 7.) During the time the tablets 83 are being pushed, with their labels 82, through the openings 33 in the pockets 25 the gumming-rollers 67 are moved inward by reason of the rotating cam 80 engaging the arms 66, so that the said rollers 67 engage against the lower portions of the labels 82 as they are drawn upward and apply a suitable quantity of adhesive substance to the lower portions of the said labels 82, while the gripper 43, which during these operations is held in a forward position, (see Fig. 3,) receives the partially-labeled tablets. The rotating cam 49 then allows the parallelogram of levers to rock outward and recede the gripper 43, which latter draws the partially-labeled tablets entirely through the openings 33, formed in the pockets 25, when the said partially-labeled tablets are carried downward with the gripper 43 through the medium of the rotating cams 49 and 53 operating the pivoted levers 44, 45, 46, and 47, forming the parallelogram, so that the rear edges of the tablets 83 and their labels 82 sweep down the curved plate 69, which has the effect of partially bringing the rear portions of the labels 82 around the rear ends of the tablets 83. (See Fig. 8.) When the tablets 83 and their labels 82 have been carried down below the curved plate 69, the operating-cam 49 of the parallelogram carries the gripper 43 forward, which brings the rear edges of the partially-labeled tablets between the guide-rails 71 and the brushes 72, when the teeth 78 of the traveling chains 73 carry the tablets and their wrappers down the said guide-rails 71 and beneath the brushes 72, which turn down the rear portions of the labels 82 over the tablets 83, and at the same time cause the two portions of each label to adhere together, (see Fig. 9,) in which condition the labeled tablets pass away down the conductor-spout 70. After the gripper 43 has delivered the tablets and their labels to the pressing-brushes 72 the said gripper 43 is moved back to its nor-

mal position through the medium of the operating-cams 49 53 and the parallelogram, ready to receive the next two tablets and their labels, when the above-described cycle 5 of operations is repeated for every two tablets, which tablets are passed through the machine in quick succession.

In employing the above-described machine for wrapping tablets in tin-foil the gumming 10 device is dispensed with, while the wrappers, which are of such a width as to overlap the ends of the tablets, are folded over the sides of the tablets in the manner and by the mechanism hereinbefore described with reference 15 to the folding of the labels over the ends of the tablets, the ends of the wrappers being afterward turned down and under the tablets by means of brushes and plow-blades located in the conductor-spout 70.

20 I claim as my invention—

1. A machine for wrapping and affixing labels around rectangular tablets, comprising in combination a tray adapted to deliver a length or strip of labels to a pair of feed-rollers, a pocket adapted to receive the strip from the rollers in an upstanding position, a horizontal knife adapted to work through a slot or gap in the pocket for severing or subdividing the labels, a traveling belt adapted 25 to feed forward the tablets, a stop against which the first tablet rests, a transverse opening formed in the pocket, a pusher adapted to carry the delivered tablet and the subdivided label through the transverse opening 30 in the pocket to wrap the upper portion of the label around the forward end of the tablet, a gumming device for applying adhesive substance to the label, a gripper adapted to receive the partially-labeled tablet and carry 35 it downward, a stationary curved plate against which the rear edge of the tablet and its label is carried by the gripper to partially bring the rear portion of the label around the rear end of the tablet, and means for completely 40 turning down the rear portion of the label 45 over the tablet and causing the two portions of the label to adhere together, substantially as set forth.

2. A machine for wrapping and affixing 50 labels around rectangular tablets, comprising in combination, frames 1 provided with cross-stays 3 and a curved plate 20, a tray 4 for the lengths or strips of labels and means for sliding the said tray 4 forward on the cross-stays 55 3 at the required times to deliver the strips over the curved plate 20, intermittently-driven feed-rollers 21, 22, for receiving the said strips from the tray 4 vertically-arranged pockets 25 for receiving the said strips from 60 the feed-rollers 21, 22, in an upstanding position, a horizontal knife 27 working intermittently through a slot or gap 26 in the pockets 25 for severing the strips, a traveling belt 34 for feeding forward the tablets, a stop 35

against which the first tablet rests, openings 65 33 formed in the pockets 25, a pusher 64 and mechanism for moving the same intermittently to push the tablets and the subdivided labels through the said openings 33 in the pockets 25 and wrap the upper portion of 70 the labels around the forward ends of the tablets, gumming-rollers 67 and means for operating the same at the required times to apply adhesive substance to the labels, a gripper 43 for receiving the partially-labeled 75 tablets and mechanism for carrying the gripper 43 with its engaged tablets downward a curved plate 69 against which the rear edges of the tablets and their labels are carried by the gripper 43 to partially bring the rear portions 80 of the labels around the rear ends of the tablets, guide-rails 71 and brushes 72 for receiving the rear edges of the partially-labeled tablets from the gripper 43, traveling chains 73 for carrying the tablets beneath 85 the brushes 72 to turn down the rear portions of the labels over the tablets and cause the two portions of each label to adhere together, and a conductor-spout 70 for delivering the completely-labeled tablets, substantially as 90 set forth.

3. In a machine for wrapping and affixing labels around rectangular tablets, the combination with vertically - arranged receiver-pockets 25, of mechanism for delivering 95 strips of labels in an upstanding position into the said pockets 25, a horizontal knife 27 adapted to sever the strips, means for feeding forward the tablets, openings 33 formed in the said pockets 25, a pusher 64 for carrying 100 the tablets and the subdivided labels through the openings 33 to wrap the upper portions of the labels around the forward ends of the tablets, means for applying adhesive substance to the labels, a gripper 43 105 adapted to receive the partially-labeled tablets and carry the same downward, a curved plate 69 against which the rear edges of the tablets and their labels are carried by the gripper 43 to partially bring the rear portions 110 of the labels around the rear ends of the tablets, and means for completely turning down the rear portions of the labels over the tablets and causing the said labels to adhere together, substantially as set forth. 115

4. In a machine for wrapping tablets in a covering material such as tin-foil, the combination with vertically - arranged receiver-pockets 25, of mechanism for delivering 120 strips of wrapping material in an upstanding position into the said pockets 25, a horizontal knife 27 adapted to sever the strips of wrapping material, means for feeding forward the tablets, openings 33 formed in the said pockets 25, a pusher 64 for carrying the tablets and the subdivided wrappers through the openings 33 to wrap the upper portions 125 of the wrappers around the forward sides of

the tablets, a gripper 43 adapted to receive the partially-wrapped tablets and carry the same downward, a curved plate 69 against which the rear sides of the tablets and their labels are carried by the gripper 43 to partially bring the rear portions of the wrappers around the rear sides of the tablets and means for turning the ends of the wrappers

down and under the tablets, substantially as set forth.

In witness whereof I have hereunto set my hand in the presence of two witnesses.

FREDERICK GROVER.
